RECORD FILING MEANS

Herbert V. Emblen and Melvin D. Baker,
San Diego, Calif.

Application March 13, 1945, Serial No. 582,506

4 Claims. (Cl. 129—20)

1

Our invention relates to record filing means and the objects of our invention are:

First, to provide a novel record filing means of maximum capacity, each file folder supporting a large number of individual record leaves and with the file folders so designed and arranged that several of these file folders may be bound together in a single volume.

Second, to provide a record filing means in which the individual record leaves are each partially exposed; thus making the indexing and alphabetical or numerical arrangement of the records simple and facilitating reference thereto;

Third, to provide such a device with many reference leaves each with considerable writing space, these leaves overlapping but arranged in the file folders so that they cannot become entangled with each other;

Fourth, to provide a folder for such a device which is complete in itself and requires no extra parts, such as dividing leaves, to prevent the individual record leaves from fouling each other;

Fifth, to provide a record filing means in which the individual record leaves may be easily removed and replaced;

Sixth, to provide a shiftable lock which may be combined with a slotted file folder to prevent individual record leaves in an incomplete column of the same from sliding along the slits in the file folder; and

Seventh, to provide a novel file folder of this class which is very simple and practicable in construction, easy to use and refer to, and generally efficient and durable in service.

With these and other objects in view as will appear hereinafter, our invention consists of certain novel features of construction, combination and arrangement of parts and portions as will be hereinafter described in detail and particularly set forth in the appended claims, reference being had to the accompanying drawings and to the characters of reference thereon which form a part of this application in which:

Figure 1 is a plan view of an expanded file folder disengaged from the binding, showing how the folder is slotted and the location of the lines along which it is folded; Fig. 2 is an end elevational view of two such file folders as illustrated in Fig. 1 properly folded and mounted by means of flexible spacer binding to rigid binder strips, which are perforated to receive the binding posts of the folder cover, not shown in the drawings; Fig. 3 is a view in perspective, of a file folder partially folded, in complete columns of individual record leaves inserted in the two slotted panels of

2

the folder and a shiftable lock inserted in the slits of a panel preparatory to being pushed upwardly to hold the record leaves above from slipping downwardly; Fig. 4 is a fragmentary detail view of an individual record leaf; and Fig. 5 is a fragmentary view of one end of a shiftable lock.

Similar characters of reference refer to similar or identical parts and portions throughout the several views:

The file folder 1, individual record leaves 2, flexible spacer binding 3, rigid binding strip 4 and shiftable lock 6 constitute the principal parts of our invention in its preferred form.

15 The file folder 1 is constructed from a rectangular sheet of material which is folded as indicated at the four dash lines in Fig. 1 to form five panels, the end panel 1a having rounded corners, the panels 1b, 1c and 1d of approximately equal width and wider than the panel 1a, and the panel 1e of considerably smaller width. The panel 1b is slotted along four lines at 1f and 1g and the panel 1c is slotted as at 1h and 1i, the said slits all being parallel to the said fold lines and all of 20 equal length extending throughout the major width dimension of the folder.

If reference now be had to the Fig. 3, it will be evident how the panels are folded together to assume the form indicated in Fig. 2. The four 25 panels 1e, 1d, 1c and 1b are each folded upwardly and to the left from the positions shown in Fig. 1 and the panel 1a is then folded upwardly and to the right to enclose the other panels.

The individual record leaves 2 may be all uniform, rectangular in shape and of a width less than one-half the width of the panels 1b and 1c. These record leaves 2 have two parallel slits 2a at each side thereof to form tabs 2b and the leaves are spaced perforated along lines collinear with 30 said slits as at 2d, the distance between the tabs 2b being very slightly less than the distance between two adjacent slits in the folder such as 1f or 1h. The portion 2e of each record leaf below the perforate lines 2d is preferably smaller in 35 accordance with the width of the tabs 2b, than the portion above said perforate lines and when these record leaves are inserted in the folder with the tabs 2b entered through the said slits in the folder the upper portion of each record leaf 2 40 is normally folded downwardly to cover the tab 2b and the lower portion 2e in the manner indicated in Fig. 3.

It will be noted that the spacing of the slits 2a will determine the spacing of the record leaves 50 when secured in operative position in the file

folder 1, and that the tabs 2b of juxtaposed record leaves abut each other on the reverse side of the file folder panel as indicated at 2b on the panel 1b in Fig. 3.

We prefer to use two columns of record leaves on both the panels 1b and 1c and the function of panel 1d will now be evident since it is folded between the panels 1b and 1c to prevent contact and possible entanglement of the tabs 2b.

The flexible spacer binding 3 secures the folder to the rigid binding strip 4, the spacer portion 3a comprisingly adhering portions of the binding between the portion wrapped around the rigid binding strip 4 and the two portions 3b secured to the folder at the contiguous edges of panels 1a and 1b, all as indicated in Fig. 2. The rigid binding strip 4 is coextensive with the hinged edge of the folder and being secured thereto as described serves as detachable securement means for binding two or more folders into one volume within any suitable cover provided with binding posts adapted to co-act with the binding post apertures 4a provided in the rigid binding strip 4 as indicated in Fig. 2.

When a column of record leaves is incomplete the leaves may tend to shift and become unfastened from the folder unless provision is made to prevent this shifting and we have provided a shiftable lock 6 insertable at one end of an incomplete column of record cards. This lock 6 is illustrated in Figs. 3 and 5 and comprises a rectangularly shaped card of any predetermined width and a length equal to a record leaf 2 and the short parallel slits 6a at each end thereof provide center tabs 6b and lateral tab 6c. The tabs 6c may be slipped into the slits in the folder as indicated at 1h in Fig. 3 and the center tabs 6b allowed to remain on the front side of the panel and then the lock may be slid along the panel, in the case illustrated upwardly, until the tabs 2b of the lowest record leaf in the column are encountered, thus locking all the record leaves in this incomplete column in place.

In use, the record leaves 2 are individually assembled in the folder 1 either before or after the folder is folded and placed with other folders with binding posts to enter the holes, the holes 4a in the rigid binding strip secured to each folder as described. The spacing portion 3a of the flexible binding allows the folder to lie flat when the volume is opened. Each record leaf will usually be lined and as noted above the upper portion of the leaf 2 will normally cover the lower portion 2e so that all indexing of the leaves should be done on the upper portion of the leaf after it is folded downwardly. The files will be placed in the provided folder all similarly disposed so that the front panel 1a of each file will be positioned to the rear of the preceding folder and thus provide a flat even surface to contact the record leaves of the panel 1b of the preceding folder.

Though we have shown and described a particular construction, combination and arrangement of parts and portions, we do not wish to be limited to this particular construction, combination and arrangement but desire to include in the scope of our invention the construction, combination and arrangement substantially as set forth in the appended claims.

Having thus described our invention, what we claim as new and desire to secure by Letters Patent is:

1. In a record file, a folder comprised of four main panels folded together, the two inner panels having slits to accommodate record leaves having tabs insertable through said slits, one outer panel foldable between said inner panels and the other outer panel folded to cover said record leaves on one side of the folder, and attachment means secured to the folder at the fold line of this last mentioned panel whereby the folder may be secured in a suitable containing cover.

2. In a record file of the class described, a folder comprising panels foldable the one on the other, parallel spaced slits in two of said panels, record leaves having laterally disposed tabs approximately intermediate the length of said leaves, and insertable through said slits to hold the said leaves in spaced relation according to the width of said tabs, the portion of each leaf above said tabs being greater than and normally folded down over the portion below said tabs.

3. In a record file, a folder comprised of four main panels folded together, the two inner panels having slits to accommodate record leaves having tabs insertable through said slits, one outer panel foldable between said inner panels and the other outer panel folded to cover said record leaves on one side of the folder, and a fifth small panel folding on said one outer panel and acting as a spacer between said one outer panel and one of said inner panels.

4. In a record file of the class described, a folder comprising panels foldable the one on the other, parallel spaced slits in two of said panels, record leaves having laterally disposed tabs approximately intermediate the length of said leaves, and insertable through said slits to hold the said leaves in spaced relation according to the width of said tabs, the portion of each leaf above said tabs being greater than and normally folded down over the portion below said tabs, the said leaves being perforated along lines collinear with the edges of said tabs.
